Jonathan Bean of Montville Maine
Letters Patent

The Schedule referred to in the Letters Patent and making part of this
same, containing a description in the words of the said Jonathan Bean
himself of his improvement in the machine for winnowing all kinds
of grain.

To all to whom these presents may come. Be it known that at
Jonathan Bean of Montville in the County of Waldo and State of
Maine have invented a new and useful improvement in a machine
for winnowing all kinds of grain, and that the following is a full and
exact description of the construction and operation of said machine
as invented by me. The advantage of this machine claims above others
now in use consists in durability, portability, and expeditious cleaning
all kinds of grain. First. The machine is made of common
boards, the size for common use is as follows. The letter A on the draft
represents one side of the machine, each side are alike, being two feet
nine inches high, and two feet six inches long. There is a piece of
hard wood board, three inches wide and two feet six inches long at the
top on the inside to nail the Boards to, and a strip one inch wide
at the bottom for the same purpose. The bottom is cut out ten inches
as having two inches wide at each end with a curve at the top
the center of the four ends and if the wheel hole is two inches and a
half from the edge and fifteen inches and three fourths from the top
the four ends is eighteen inches in diameter which makes a projection of six
and a half inches, at the other end there is a piece cut out fifteen inches
long and three inches wide from the bottom which serves for a handle.

The wheel hole is cut out from the center of the four ends ten
inches, and three fourths in diameter. B represents the wheel it
is fifteen inches in diameter, is one inch thick, the edge is a little round
edged, a piece of hard wood is fast across, two inches wide, five eighths
of an inch thick, and seventeen and a half inches long screwed on the
handle goes through it, and through the wheel. The wheel is hung on the

146.

right side of the machine one inch and a half from the top, and none from the end on a shaft of hard wood one inch and a fourth in diameter, and nineteen inches long goes through the opent side with a grub, one five eights of an inch in diameter, a peg goes through to keep it in. C represents the wheel, it is three and a half inches in diameter one inch and a fourth thick, with a cap on the outer side projecting $\frac{1}{3}$ of an inch to keep the strap on the wheel is attached to the shaft and is on the right side. D represents the strap it is made of cow leather seven eights of an inch wide, about seven feet long with a buckle to keep it together, this goes round the wheel and round the wheel. E represents the shaft is seventeen inches long the guides are either wood or iron with a crank at one end, it is turned around in the middle and at each end a space is left one inch and a half square for the arms to go through three inches from the ends, the arms are four in number five eights of an inch in diameter and eighteen inches in length, the shaft is in the centre of the fan curb six & a half inches from the edge and fifteen inches and three fourths from the top. F represents the posts that the shaft runs in, they are two inches wide and one and a half thick, and twelve inches long, these are let into the sides ¹⁵⁰ across the centre of the wind box and made fast at the ends with screws. G represents the lining, it is a board cut in the form of a fan curb eighteen inches in diameter in the form of a circle except one corner which is left six inches to let out the wind at the top, one of these is attached to the inside of each side of this machine to form the fan curb, the centre of which is where the shaft runs. H represents the fan curb, it is eighteen inches in diameter, the centre is fifteen inches and three fourths from the top, and six and a half from the edge, it is made by bending on thin boards & nailing them to the lining ~~accepting~~ six inches to let out the wind. I represents the first partition ten inches wide and seventeen and a half inches ^{edge} long, seven inches of the ^{edge} is hollowed out and forms a part of the fan curb and is placed vertical across

the machine and mailed onto the lining at each end, J represents the slide it is a piece of broad sixteen inches long and two and a fourth wide & is placed between the first and second partition so as to shute the grain out under the right side of the machine. K represents the second partition it is eleven inches wide and seventeen and a half inches long and is set two and a fourth from the first partition. L represents the draw to catch the foul seed, it is six inches wide and five deep and goes in on the right side of the machine by the side of the second partition and goes through to the other side of the machine. M represents the first fall board, it is nine and a half inches wide and seventeen and a half inches long, one edge is ground out and sets on the edge of the draw, the other edge goes out to the edge of the fine line to run the foul seed into the draw. N represents the second fall board, it is eighteen inches long nine and a half wide, the sides of the machine are grooved out to receive it so it may move up and down as occasion may require. O represents a board across the machine under the fan curb is eight and a half inches wide and eighteen and a half long. P represents a board across the machine above the fan curb is eighteen and a half inches long, and eleven and a half wide the hopper sets on the upper edge of this. Q represents one end of the hopper it is seventeen inches long at the top and is nine at the bottom and is seven and a half deep, both ends are slanted alike. R represents the other end of the hopper is seventeen inches long at the top and nine and three fourths at the bottom, is six and a half deep, these ends are slanted so as to receive the sides. S represents the two sides of the hopper, they are twenty one inches long at the top and thirteen at the bottom and eleven inches deep, both ends are slanted alike, the hopper is mailed together and sets in the top of the machine, one end rests on the board that goes across the machine above the fan curb, the other end rests on a board that is screwed on to the top across the ma

1118.

shoe six inches wide. A represents the topper follower it is fifteen inches and a half long twelve wide and is nine inches long at the bottom and is the same width up three inches from the bottom and has a joint in the middle and hung with a ring to turn on B, represents the sides of the shoe it is twenty five and a half inches long on the top the outer end is five inches and three fourths wide, then it is slanted on the under side fifteen inches and a half and is twelve inches wide, it is then cut away with a right angle with the top to three inches wide from this to the end is a segment of half of an inch and is one inch wide at the end, the two sides are alike they are grooved out on the inside to receive the wires, the lower one is half an inch from the edge, the second groove is a fourth of an inch from the first at the outer edge and at the other it is five and a half inches from it so that the upper shoe will stand nearly horizontal when hung. The shoe is hung in the top of the machine, where the fore curb is, and two and a half from the top and four and a half at the other end, the shoe is hung by having a piece of hard wood attached to the bottom of the shoe in the centre and projecting one inch and a half through it and a peg is fixed in a small piece of wood two and a half deep and nailed to the board that goes across the top of the machine above the fore curb. C represents ^{the} the bottom is a thin board thirteen and a half inches square, and is nail ed on to the under and inner part of the shoe sides to confine them, a stick goes across the shoe between the wires and pegs in at the outside to keep it from spreading. D represents six large wires, the size is No 10, eleven inches long these are fed through a thin piece of hard wood, one inch wide made fast at each end to the sides of the shoe and forms a part of the shoe bottom, the wires run out over the wires and three inches above them and serve to keep the wires from digging. E represents a board fifteen inches wide and nineteen inches long and is placed across the

3/31/1836 9558X

449

machines under the handles. 1. represents the shoe shaker, it is a piece of round iron half an inch in diameter, seven inches long with an arm at each end three inches long with a hook at the end of each arm. The arms stand nearly at right angles with each other. holes are punched in each end to receive the iron points so that it hangs on. the points that it hangs on are made fast in pieces of hard wood one inch and a half wide, and screwed on to the side of the machine opposite the shoe. the upper point is a screw, a hole is made through the side of the machine and a piece of hard wood four inches long goes from the back of the shaker to a piece of iron screwed on to the side of the shoe and a screw twenty inches long goes from the other hook of the shaker to the crank which is one inch long. 2. represents a shutter; it is a thin piece of board nineteen inches long and three wide and is fastened with a screw to the under part of the left side of the machine and comes out under the bottom of the right side and covers the part where the grain comes out, and may be moved as occasion may require. 2. 1 represents the fans four in number sixteen inches long and six inches wide, and one fourth of an inch thick. these are nailed on to the arms. No 1 represents a petition under the bottom of the centre is two feet three inches long and ten inches wide. No 2. represents the fine sieve, it is thirteen and a half wide and fifteen and three fourths inches long, made of wire weaving, the size is No 24. the mashing ten to an inch nailed to the rim which is one inch wide and half of an inch thick, this sieve goes at the bottom of the shoe to take out the foul seed. No 3 represents the second sieve it is thirteen and a half inches by fourteen and a half, the wire is No 21. and the mashing is four to an inch, the rim is one inch wide, and half of an inch thick. No 4 represents the coarse sieve, is thirteen and a half inches by fourteen and a half the wire is No 20, and the mashing ten to an inch the rim is one inch wide and half of an inch thick.
